(57) **CLAIM**

We claim, the ornamental design for a watch, as shown and described.

DESCRIPTION

FIG. 1 is a perspective view of a watch, showing my new design;

FIG. 2 is a top plan view of the watch;

FIG. 3 is an end elevational view of the watch;

FIG. 4 is a plan view of the bottom of the watch.

FIG. 5 is an end elevational view showing the end opposite that shown in FIG. 3;

FIG. 6 is a left side elevational view of the watch; and,

FIG. 7 is a right side elevational view of the watch.

The broken lines in the drawing are for illustrative purposes only and form no part of the claimed design.
